REFRIGERATION

Application filed January 27, 1928. Serial No. 249,793.

This invention relates to refrigerating systems, and particularly concerns an improved refrigerating unit for use in refrigerating systems of the evaporation type.

5 This application is a continuation in part of my copending application, Serial No. 143,-900, filed October 25, 1926, now Patent No. 1,670,756 of May 22, 1928.

10 In one general type of modern refrigeration system, apparatus is provided for subjecting a suitable refrigerant to a cycle of operations, the refrigerant being successively compressed, liquefied and cooled in a condenser, passed through a suitable expansion 15 valve and delivered to a refrigerating or heat absorbing unit where it is gasified, the gaseous refrigerant being again returned to the compressing means. The heat absorbing or refrigerating unit is preferably installed in the 20 cooling chamber of a refrigerator, or is otherwise disposed in a space where it is desired to absorb heat.

The refrigerating or heat absorbing unit used in a system of the type described generally comprises a suitably formed container within which the liquid refrigerant evaporates or gasifies, and this evaporation absorbs heat through the walls of the container from the refrigerated space. It is essential to the 30 efficient operation of a system of this type that the walls of the refrigerating unit be constructed of a good heat conducting material, and it is further desirable that the transfer of heat to the refrigerant be facilitated by constructing these walls of only such 35 thickness of material as will provide sufficient strength for safe and satisfactory operation.

In refrigerating systems of the type described, the refrigerating cycle is not continuous, the refrigerant being liquefied and supplied to the refrigerating unit for a predetermined time, after which the compressing means stops and the absorption of heat is continued by the evaporation of the liquid refrigerant in the refrigerating unit. When a predetermined quantity of liquid refrigerant has evaporated, the compressor again starts, and a fresh supply of liquid refrigerant is delivered to the refrigerating unit.

The starting and stopping of the compressing means is controlled by suitable apparatus such as a thermostatic device responsive to the temperature in the refrigerated space.

Due to the intermittent operation of the 55 system, and due to the fact that the power for operating the compressor may be temporarily discontinued for various reasons, the evaporation of the refrigerant and the consequent absorption of heat thereby is not constant, 60 and the temperature of the refrigerator or other cooled space consequently varies between undesirably wide limits.

With the above and other considerations in mind, it is proposed in accordance with the 65 present invention to provide a refrigerating unit in which the heat transfer through the walls is rapid and efficient, and in which means are provided for stabilizing the 70 temperature of the unit and of the refrigerated space during variations in the rate of evaporation of the refrigerant. More specifically, it is proposed to provide a refrigerating 75 unit comprising a container having comparatively thin walls, and to enclose within such container a mass of material having a large heat absorbing capacity, which means acts as a cold reservoir for absorbing the heat when the rate of evaporation of the refrigerant decreases.

80 Other specific objects, advantages and characteristic features of the present invention will become apparent as the description thereof progresses.

85 In describing the invention in detail, reference will be made to the accompanying drawings, in which;

Figure 1 is a side view, partly in section, of the heat absorbing unit of the present invention; and

90 Fig. 2 is a sectional view taken along the line 2-2 of Fig. 1 and viewed in the direction of arrows.

95 Referring to the drawings, a refrigerating unit embodying the present invention has been shown, it being understood that the invention is not limited to the specific unit disclosed.

100 The heat absorbing unit shown in the drawings includes a cylindrical drum or

header 1 which is preferably disposed horizontally and is provided with a suitable removable cover or head 2, secured to one end thereof by the bolts 3, as shown, a gasket 4 being provided to insure a tight closure. The head 2 of the drum 1 is provided with an enlarged portion 6 carrying suitable outlet connections (not shown) and having an outlet passage 7 therethrough. A cut-off valve V is preferably provided in the passage 7, and swivel mechanism 9 carrying an outlet pipe 10 supported by a float 11 is supported on the inner face of the head 2. The cut-off valve V may take any suitable form, and as shown, 15 comprises a valve stem 12 surrounded along its outer portion by the packing material 13 and carrying a gate or plug 14 for co-operation with the opening 15 leading to the swivel mechanism 9. The outer end of the valve 20 stem 12 is preferably enclosed by a cap 16 to prevent any unauthorized or accidental manipulation of the valve and to prevent the leakage of refrigerant therethrough. The swivel mechanism 9 and the float supported 25 outlet pipe 10 form no part of the present invention, and it is sufficient in connection with the present invention to understand that the vaporized refrigerant is conducted out of the header 1 through the pipe 10 and the 30 swivel mechanism 9.

The cylindrical wall of the header 1 is provided with three rows of equally spaced openings 17, extending from end to end thereof. Two of these rows of openings 17 are located 35 on the sides of the header 1 along a horizontal plane through the axis thereof, and the third row extends along the lower face of the cylindrical wall as shown in the drawings. The openings 17 communicate with three interconnected rows of tubular passages 18, these 40 passages being formed to surround two freezing chambers 19, as most clearly shown in Fig. 2. As more fully described in my co-pending application, Serial No. 143,900, the 45 rows of passages 18 are preferably formed by the cooperation of three corrugated sheets of thin metal 21, 22 and 23, the inner sheets 22 and 23 having ledges 24 formed thereon for supporting shelves or trays 25 within the 50 freezing chambers 19. An inlet connection 26 is provided in the sheet 21 at the bottom of the unit to conduct the liquefied refrigerant thereto.

Referring now more particularly to the 55 heat absorbing or temperature stabilizing feature of the present invention, a large solid body 5 is enclosed within the refrigerating unit in direct contact with the refrigerant therein. This body has been shown located 60 within the header 1, but could be placed at any other convenient point. The body 5 is preferably composed of a material having a high heat absorbing capacity, such as cast iron, and is preferably shaped to conform 65 with the inner wall of the header 1. Suitable

spacing means such as the legs 27 are formed integral with or suitably secured to the body 5, and serve to space the body from the header walls, thereby permitting the circulation of the liquid and gaseous refrigerant between 70 the body and the adjacent walls of the header. In this manner, the refrigerant comes into contact with substantially the entire interior surface of the refrigerating unit, and the absorption of heat through the header walls 75 is not retarded by the temperature stabilizing body.

Suitable means, such as a compressor and a condenser, are provided to draw the vaporized refrigerant from the header through 80 the passage 7, and to liquefy the refrigerant and return it to the refrigerating unit through the inlet connection 26. As explained above, the refrigerant liquefying apparatus preferably operates intermittently. 85 The liquid refrigerant is supplied to the refrigeration unit until a predetermined amount has collected therein, whereupon suitable control means operated to stop the liquefying apparatus and the refrigerant 90 gasifies in the unit to produce the desired heat absorbing effect. As the refrigerant liquefying apparatus and the devices for controlling such apparatus are well known in the art, a detailed description thereof will not be given 95 herein. Suitable apparatus for this purpose is shown in my copending applications, Serial No. 142,846, filed October 20, 1926; now Patent No. 1,684,810 of Sept. 18, 1928, Serial No. 149,844, filed November 22, 1926, and Serial No. 149,845, filed November 22, 1926; now Patent No. 1,704,352 of March 5, 1929.

In the operation of a refrigerating system including the improved refrigerating unit of the present invention, the evaporation of 105 the liquid refrigerant within the unit rapidly absorbs heat through the thin walls of the unit, thereby quickly lowering the temperature of the refrigerated space to the desired degree. At the same time, heat is absorbed by the refrigerant from the body 5, and the temperature of this body is thereby reduced to a very low value. As the amount 110 of liquid refrigerant in the refrigerating unit is reduced by evaporation, the rate of heat absorption decreases and the temperature of the unit and of the surrounding refrigerated space tends to rise. At this point, 115 heat is absorbed by the body 5, and the temperature of the unit and of the refrigerated space is thereby maintained at a suitable low value until a fresh supply of liquid refrigerant is delivered to the unit. Although the body 5 may be thus heated to a fairly high 120 temperature at the time that the fresh supply of liquid refrigerant is delivered to the unit, the absorption of heat by the refrigerant through the walls of the header 1 is not appreciably delayed or interfered with, as 125 the liquid and gaseous refrigerant comes into 130

direct contact with the entire interior surfaces of the header walls.

In the manner described, the heat absorbing body 5 serves to stabilize the temperature of the refrigerated space and to prolong the period during which the refrigerant liquefying means may remain idle. Due to the thin walls of the refrigerating unit, heat is rapidly and efficiently transferred to the interior thereof, and the refrigerating unit of the present invention thereby combines the advantageous features of rapid heat absorption and high heat absorbing capacity or temperature stability.

Although the heat absorbing unit of the present invention has been described in connection with one specific construction, it should be understood that the invention is not limited in its scope to the embodiment shown, and that many changes, modifications and additions may be made without departing from the scope of the invention as defined by the appended claims.

I claim:

1. In a refrigerating system of the type in which a liquefied refrigerant is periodically supplied to a refrigerating unit and evaporated therein, a refrigerating unit comprising a container having thin walls of heat conducting material, and a separate solid mass of metal having a large heat absorbing capacity enclosed within said container for cooperating with the refrigerant in maintaining the unit at a substantially constant low temperature regardless of interruptions in the supply of said liquid refrigerant to the unit.

2. In a refrigerating unit, a header, a plurality of circulating passages connected with said header, and a solid mass of metal having a large heat absorbing capacity disposed within said header and spaced from the walls thereof for cooperating with a refrigerant in maintaining the unit at a low temperature.

3. A refrigerating unit comprising a header, a plurality of passages communicating with said header, said header and said passages having thin walls of heat conducting material, a solid mass of metal having a large heat absorbing capacity disposed within said header for cooperating with a refrigerant in maintaining the unit at the required low temperature, and means for spacing said mass of metal from the walls of said header to permit direct contact between the refrigerant and substantially the entire interior surface of said header.

4. A refrigerating unit for use in refrigerating systems of the type in which a quantity of liquefied refrigerant is periodically supplied to the refrigerating unit and evaporated therein comprising a container having thin metallic walls for rapidly transferring heat from the surrounding medium to the refrigerant, and a separate solid mass of

metal enclosed within said container and spaced from the walls thereof for cooperating with the refrigerant and maintaining the temperature of the unit substantially constant during variations in the rate of evaporation of the refrigerant.

In testimony whereof I affix my signature.

ALFRED MORRIS THOMSON.
